UNITED STATES PATENT OFFICE.

JOHN CLAYTON BACKUS, OF SMETHPORT, PENNSYLVANIA.

BOWLING-PIN-SETTING DEVICE.

1,319,035.

Specification of Letters Patent.

Patented Oct. 21, 1919.

Application filed April 7, 1919. Serial No. 288,032.

To all whom it may concern:

Be it known that I, JOHN CLAYTON BACKUS, a citizen of the United States, residing at Smethport, in the county of Mc- 5 Kean and State of Pennsylvania, have invented certain new and useful Improvements in Bowling-Pin-Setting Devices, of which the following is a specification.

This invention relates to bowling pin setting devices and is designed primarily as 10 an improvement upon the setting devices shown in my prior Patents No. 771,963 issued October 11, 1904 and No. 821,276 issued May 22, 1906.

15 The patented devices as well as the improved device are characterized by positioning blocks arranged about openings in the platform or frame of the device and which blocks are designed to engage the 20 sides of pins disposed within said openings so as to accurately center the pins upon their respective alley spots, the blocks being yieldably held in an inward direction by means of springs and being supported by 25 arms hinged to attaching members upon the under side of the frame or platform. This particular type of pin setting device depends for accuracy in the performance of its functions, upon the accurate swinging 30 upon their hinge connections, of the arms which support the positioning blocks for if these hinge connections become even slightly disarranged or distorted or if they become loose, the corresponding pin or pins will 35 not be accurately set upon their spots and repairs then become necessary. This dis- arrangement is liable to occur more or less frequently from several causes. The attendant may carelessly lower the frame or 40 platform onto "dead wood" causing a dis- tortion or breakage of such of the position- ing blocks as come into engagement with the fallen pins constituting the "dead wood"; a bowler may deliver the ball before the 45 frame or platform has been elevated clear of the alley thus causing the ball to strike one or more of the positioning blocks causing similar damage; or, the hinge connections may become worn after the device has been 50 used for a considerable period of time. In any event whenever from any cause there is a disarrangement of any one or more of the positioning blocks or the hinges for the same, the entire device becomes temporarily 55 useless and the particular block or blocks

which have suffered injury or disarrange- 60 ment must be removed and new ones sub- stituted therefor. In my patented struc- tures this replacement could only be effected by removing a number of screws which se- 65 cure the fixed member of the hinge to the frame or platform and the reattachment of a complete new positioning unit or of the disconnection from the hinge member of the supporting arms for the block and the 70 substitution of a new block by connecting its said supporting arms with the said hinge member. To make this repair necessitates the temporary shutting down of the alley 75 which is, of course, disconcerting and an- 80 noying to the bowlers and means a loss of income to the proprietor. In considera- 85 tion of the foregoing it is the primary object of the present invention to provide a hinge connection between the frame or platform 90 of the device and the positioning block which will permit of the removal of any individual block and the replacement of a new one in a moment's time and without the necessity of loosening any screws or other fastening devices or employing any tools whatsoever. Thus when any block be- 95 comes damaged it may be almost instantly removed and a new one put in its place. Thus with my improved device the replace- 100 ment of one or even several of the position- ing blocks will not act to delay the bowlers for any longer period of time than would ordinarily be consumed in the setting of the pins by hand.

In the accompanying drawings:

Figure 1 is a plan view illustrating in a general way the arrangement of the units of the device;

Fig. 2 is a side elevation of one of the 95 positioning devices illustrating the same in full lines in lowered position and in dotted lines in partly elevated position;

Fig. 3 is a perspective view of one of the 100 positioning devices inverted so as to better show the hinge connection embodying the invention;

Fig. 4 is a group perspective view illus- 105 trating the parts of one of the devices disconnected.

In the drawings, the numeral 1 indicates in general the frame or platform of the de- 110 vice which may be of any desired construc- tion and which is formed with pin receiving

2
which the pins are to assume when properly spotted upon the alley. A suitable number of the positioning devices embodying the invention are arranged about each of these 5 openings so that the blocks of the said devices will engage the sides of pins thrown or placed within the openings. The improved device includes a positioning block indicated by the numeral 3 and formed with 10 a concave face 4 to engage the side of the pin to be positioned, this block being of the same form as the blocks disclosed in my said prior patents. Secured to the opposite sides of each block near the upper 15 end are supporting arms 5 and these arms project beyond the outer face of the block as in the patented structures and constitute hinge members as in the patented structures. For a purpose to be presently explained 20 each arm 5 is formed in its extremity with a relatively deep notch 6 and in its lower edge inwardly of its extremity with a notch 7 having an abrupt wall 8 forming a shoulder extending substantially at right 25 angles to the lower edge of the arm.

The other member of the hinge and with which member the arms 5 are detachably connected comprises an attaching plate 9 which is permanently secured in any suitable manner 30 to the under side of the frame or platform 1 as clearly shown in Fig. 2 of the drawings. This plate 9 at its side which is located next adjacent the respective opening 2, is formed with a depending flange 10 having lateral stop shoulders 11 engageable by 35 the arms 5 so as to limit the downward swinging movement of the said arms. A pintle pin 12 is fitted permanently at its ends in openings in ears 13 formed to project below 40 the under face of the attaching plate 9 and this pin is of such diameter as to seat within the notches 6 in the arms 5 when the arms are disposed at their extremities opposite the end portions of the pintle pin and 45 are shifted transversely of the axis of the pin. Springs 14 are coiled at their intermediate portions about the end portions of the pintle pin 12, one end 15 of each spring engaging against the under side of the attaching plate 9 and the other end 16 of each spring, which end is located next adjacent the respective arm 5, being extended beneath 50 the plate 9 in the direction of the flange 10 and being formed with a hooked extremity 55 17, the hooked extremities being turned outwardly laterally. When the arms 5 are disconnected from the pintle pin 12, the ends 16 of the springs will bear against the under face of the said plate 9 due to the resiliency 60 and tension of the springs. In proportioning the parts the distance between the inner ends of the notches 6 and the walls 8 of the notches 7 is substantially equal to the lengths of the ends 16 of the springs so that 65 as a result, in assembling the parts, when

the arms 6 are engaged at their extremities with the pintle pin so that the pin is received within the inner ends of the notches 6, the ends 16 of the springs may be sprung away from the plate 9 and their extremities 17 70 engaged in the notches 7 in the said arms and behind the walls 8 of the said notches. Due to the proportioning of the parts the arms 5 will be positively held by the springs against disengagement from the pintle 12 75 and may have free pivotal movement about the said pin as an axis. When it is desired to remove any one of the positioning blocks for repairs or replacement, it is only necessary to spring the ends 16 of the springs 80 downwardly so as to disengage their extremities from the respective arms 5 whereupon the arms may be slid out of engagement with the pintle pin 12.

From the foregoing description of the invention it will be understood that merely by disengaging the ends 16 of the springs 14 from the arms 5, the block supported by these arms may be instantly disconnected from the member 9 which is permanently 90 fixed upon the frame or platform of the device. Also the block may be readily replaced or another one substituted therefor, and while all of the advantages of an accurate hinge joint are obtained, there is no 95 permanent connection between the member 9 and the positioning block. In this case, of course, the springs serve a dual function. Of course, due to the provision of the readily separable hinge connection herein disclosed, 100 any individual positioning block may be disconnected from the frame or platform 1 and either promptly repaired, or a new one may be readily substituted therefor, it being only necessary, as before stated, to disengage the 105 hooked extremities 16 from the arms 5 so that it is not necessary to interrupt the game or shut down the alley for any considerable period of time while making repairs. Of course, the springs serve to normally hold 110 the block in the full line position shown in Fig. 2 of the drawings and any downward movement of the blocks with relation to the frame or platform 1, as for example to the dotted line position in said figure, will be 115 against the tension of the springs.

Having thus described the invention, what is claimed as new is:

1. A hinge support for the positioning member of a pin setting device comprising 120 a hinge member including a pintle, a hinge member pivotally separably engageable with the pintle, and a spring upon the pintle engageable with the last mentioned hinge member, when the members are assembled, to 125 swing one member with relation to the other and to hold the members against separation.

2. A hinge support for the positioning member of a pin setting device comprising a hinge member including a pintle, a hinge 130

member having a notch to receive the pintle whereby the members may be pivotally and separably connected, and a spring carried by the first mentioned hinge member and having an end engageable with the last mentioned hinge member to swing one member with relation to the other and to hold the members against separation.

3. A hinge support for the positioning member of a pin setting device comprising a hinge member including a pintle, a spring coiled about the pintle and having one end engaging the said member, and a second hinge member separably engageable with the said pintle, the said spring having its other end engageable with the last mentioned hinge member whereby to swing one member

with relation to the other and to hold the members against separation.

4. A hinge support for the positioning member of a pin setting device comprising a hinge member including a pintle, a hinge member including an arm pivotally and separably engageable with the pintle and having a shoulder, and a spring coiled about the said pintle and engaging at one end against the first mentioned hinge member and at its other end engageable with the said shoulder whereby to hold the hinge members against separation, the spring coacting with the members to swing one member with relation to the other.

In testimony whereof I affix my signature.

JOHN CLAYTON BACKUS. [L. S.]
